DISPLAY CARD

William H. Weil, Hollis, N. Y., assignor to
Stransky Products Corporation, New York,
N. Y., a corporation of New York

Application June 12, 1934, Serial No. 730,182

3 Claims. (Cl. 206—79)

This invention relates to display cards or sheets more particularly adapted for displaying supporting attachments or the like for pictures, cards, calendars, etc., the attachments being adapted 5 to be engaged with picture or like hangers, so that the articles to which the attachments are applied may be supported on a wall or elsewhere. The display card of the present invention may have means for supporting picture hangers or 10 the like in the manner described and claimed in prior U. S. Letters Patent No. 1,581,886, granted on April 20, 1926 to Jacob Strand, such display means being adapted to be combined with means for displaying picture supporting attachments. 15 Objects of the invention are to make it possible to combine for display on one card a series of picture hangers or the like and a series of picture supporting attachments or the like, they preferably being arranged in an associated dis- 20 play in such way as to indicate that one of the picture hangers is usable with a picture supporting attachment; and furthermore to provide simple and relatively inexpensive means for supporting picture supporting attachments for display, 25 particularly in association with displayed picture hangers.

These being among the objects of the present invention, the same consists of certain features of construction and combinations of parts to be 30 hereinafter described and then claimed with reference to the accompanying drawing illustrating a preferred embodiment of the invention, wherein

Fig. 1 is a plan of the card or sheet, showing 35 the condition thereof before the articles to be displayed are mounted thereon;

Fig. 2 is a plan of the card or sheet with picture hangers and picture supporting attachments mounted thereon for display;

Fig. 3 is a plan of the back of the assembly 40 shown in Fig. 2;

Fig. 4 is an enlarged detail section on line 4—4, Fig. 2; and

Fig. 5 is an enlarged detail horizontal section 45 on the line 5—5, Fig. 2.

In the drawing, the card or sheet 10 is of flexible material such as card board or other flexible sheet material. The card 10 is provided with a plurality of tongues 11 which are cut out there- 50 from by forming slits around the tongues, as shown in Fig. 1, except at corresponding sides where they are left integral with the card, preferably in the manner disclosed in aforesaid patent. These tongues 11 are parallel with each other at suitable distances apart and extend as a

series preferably along a straight line, and they may be bent out at right angles to the face of the card 10 as shown in Figs. 2 and 4.

There is also formed in the card 10 a plurality of pairs of slots 12, 13 which extend along a line generally parallel with the plurality of tongues 11. In each pair of slots 12, 13 the slots thereof are curved outwardly the one from the other as clearly shown in Figs. 1, 2 and 3 so that their incurved sides mutually face. The plurality of pairs of slots 12, 13 is preferably so arranged that the separate pairs are in stepped relation to each other, although as a whole they generally extend parallel with the plurality of tongues 11. The arrangement is preferably such that the planes of the tongues 11 when bent out at right angles to the face of the card 10 are presented edgewise to the plurality of slots 12, 13, so that the planes of the tongues intersect the plurality of slots 12, 13 along lines between the slots of the respective pairs 12, 13. In other words, in each pair of slots 12, 13 there is one of them to one side and the other of them to the other side of the outwardly deflected tongues 11, for reasons to be made clear.

To facilitate engagement of the articles with those portions of the card 10 which are provided with the slots 12, 13, slits 14 extend from about the mid-lengths of slots 13 in a direction laterally away from the out curved side of each such slot 13.

The arrangement of the tongues 11 and the slots 12, 13 is preferably such that picture hangers or the like and picture supporting attachments or the like may be arranged in quite close 35 relation, the balance of the face of the card 10 being adapted to be used for advertising or the like.

Picture hangers 15 are adapted to be supported in a series by the tongues or tabs 11, these being 40 of open shape of sheet metal adapted to be supported on their edges against the face of the card, with the tongues 11 extending thereinto, as shown in Figs. 2 and 4, the construction and arrangement in these respects being preferably 45 in accordance with aforesaid patent. Nails 16 are passed through holes in the hangers 15 and through the tongues 11 so as to support the hangers in display position upon the card.

A series of picture or like supporting attach- 50 ments 17, preferably of sheet metal, is supported upon the card 10 by means of the parts of the card formed by the slots 12, 13. Referring to Fig. 2 it will be seen that these attachments 17 are supported edge to edge and substantially 55

in alignment with the hangers 15. Each of the attachments 17 is provided with an annular ring or loop 18, the planes of the hangers 15 mounted on edge on the card extending approximately along the diameters of the rings 18. Each ring or loop 18 is adapted to be subsequently engaged over the hook of one of the series of picture hangers.

Each attachment 17 is also provided with a substantially flat base 19 which is formed integrally with the ring 18, each such ring being preferably channeled in cross-section, as shown in Fig. 4, so that its smooth convexed surface is at the front of the card, while the channel is presented towards the face of the card. Hence the back of the ring 18 is flush with the back of the base 19, so that the attachment becomes a flat article which may be mounted squarely upon the card face foremost.

20 The base 19 of each attachment 17 is formed to provide ears 20 which extend laterally of the diameter of the ring of the corresponding attachment. From within the base 19 and ears 20 prongs 21 are struck out forwardly, these prongs serving as means for securing the picture supporting attachment 17 to a picture or other object.

To mount the series of attachments 17 on the card 10 the ears 20 of each attachment are passed through the card so as to extend from front to back of the card, through the slots 12, 13, thereby positioning the series of attachments in relation to the series of hangers 15 preferably in about the relation shown. The distance between the slots 12, 13 of each pair is less than the distance between the extreme edges of the ears 20, so that when each attachment is properly mounted on the card 10, the extremities of the ears will protrude at the back of the card as shown in Fig. 3. The radial slits 14 facilitate the insertion of the attachments into the slots 12, 13, the ears which go into the slots 13 being inserted last and the slits 14 enabling the deformation of the card or flexing thereof in such way as that the insertion of the attachment is facilitated without having to tear or injure the card, the flexibility of the latter further assisting in this connection.

By curving the slots of each pair 12, 13, in the way described, flexible tabs 12a, 13a integral with the ears and extending away from each other are provided, so that when a pair of the slots is properly engaged by the ears 20 of an attachment the flexible tabs will be deflected rearwardly, leaving exposed at the front a large area of the attachment.

It will be noted that when hangers 15 and attachments 17 are displayed as shown in Fig. 2, the series of picture supporting attachments will be close to the series of picture hangers and their close juxtaposition will point out of itself to the ultimate user that the supported articles are to be used together. The preferred positioning of the supported articles will clearly indicate the function of the articles 15 as picture hangers while the position of the attachments

17 will indicate that they are to be used preferably jointly with the picture hangers. In the drawing four sets including a picture hanger and an attachment 17 are shown, although it is obvious that their number may be changed as desired. 5

When it is desired to use a picture hanger and an attachment, the nail for the hanger is removed so that the hanger is detached from the card. An attachment may then be readily removed from the card. There is thus obtained 10 a set of the picture or other such articles, the prongs of the attachment being pressed through the picture or the like and then upset to secure it thereto, and the nail being then inserted through the holes of the hanger and driven into 15 a wall at the position desired, whereupon the ring of the attachment may be engaged over the hook of the hanger to suspend the picture or the like on the wall.

It is obvious that the invention as shown and described is capable of more or less modification without departing from the scope of the appended claims.

What I claim as new is—

1. A display card of flexible sheet material provided with two slots spaced apart side by side and outwardly directed tabs defined by the slots, in combination with a picture supporting attachment having a substantially flat base extending laterally from opposite sides of the attachment to provide a pair of ears, the ears being engaged in the slots and over the tabs, whereby to fix the attachment removably in display position upon the card. 25

2. A display card of flexible sheet material provided with two slots spaced apart side by side, in combination with a picture supporting attachment having a substantially flat base extending laterally from opposite sides of the attachment to provide a pair of ears, and the ears having prongs struck out forwardly therefrom, the ears being engaged in the slots, whereby to fix the attachment removably in display position upon the card, and the slots being curved away from each other with their curved inner sides 40 mutually facing to extend partly around and locate the prongs within the curves when the attachment is so mounted. 45

3. A display card having a plurality of parallel tongues extending from one surface thereof for supporting picture hangers for display, and provided with a plurality of pairs of slots for supporting picture attachments for display on such surface, the plurality of pairs corresponding in number with the plurality of tongues, the plurality of tongues and the plurality of attachments being offset the one from the other and arranged in substantially parallel relation, the planes of the tongues intersecting the plurality of slots along lines between the slots of the respective 60 pairs, and the tongues and slots being arranged sufficiently close together to support picture hangers and picture attachments in juxtaposed relation. 55
